FRANK ORTH, OF INDIANA HARBOR, INDIANA.

ARCH CONSTRUCTION FOR FURNACES.

No. 880,910.

Specification of Letters Patent. Patented March 3, 1908.

Application filed May 6, 1907. Serial No. 371,983.

To all whom it may concern:

Be it known that I, FRANK ORTH, a citizen of the United States of America, residing at Indiana Harbor, in the county of Lake and 5 State of Indiana, have invented new and useful Improvements in Arch Constructions for Furnaces, of which the following is a specification.

This invention relates to arch constructions 10 for furnaces, designed more particularly for use in open hearth, steel, glass, and other melting furnaces, and one of the principal objects of the invention is to provide an arch construction of greater strength and durability than the ordinary arch construction, 15 and which will be more readily repairable when partially burned out.

In the usual construction of arches, when the inner side of the arch wall is burned away 20 irregularly at different points, the unequal distribution of weight would thrust the arch out of its proper radius, and hence, there would be an outward movement at some points and an inward movement at other 25 points, which would eventually cause the arch to collapse. Since an open hearth arch usually burns out irregularly, it is impossible to determine in advance what point or points will burn out first. In the construction of 30 my improved arch, I reinforce the arch with ribs which will support the arch when it is burned away to quite a thin shell. It is to overcome, to a great extent, this defect in furnace arches, and to facilitate the repairing 35 of arches partially burned away, that my invention has for its principal object. This and other objects may be attained by means of the construction illustrated in the accompanying drawings, in which:

40 Figure 1 is a plan view of a furnace made in accordance with my invention. Fig. 2 is a side elevation and partial longitudinal section of the same. Fig. 3 is a transverse section on the line 3—3, Fig. 1, looking in the 45 direction indicated by the arrows.

Referring to the drawing for a more particular description of my invention, the numeral 1 designates the side walls of the furnace, and 2 is the arch. Extending along the 50 side walls at the top on both sides is an angle iron brace 3, and the buck stays 4 comprise two channel irons provided with a reinforcing plate 5 and brace rods 6 extending through said plates between the angle iron beams of 55 the buck stays.

The arch 2 consists of the bricks or blocks 7 and the intermediate arched ribs 8, said ribs extending above the upper surface of the bricks, as shown in Fig. 2. The end portions of the arch are oppositely inclined, 60 as shown at 9, and longitudinal stay rods 10 extend from end to end of the furnace, and being connected to buck stays in a manner similar to those already described. The arched ribs 8 may be formed in one single 65 piece, as shown at the left in Fig. 1, but it will be obvious that these ribs may be formed in sections. The ends of the arch abut against the skew-backs 11.

It will be obvious that any suitable number of ribs 8 may be used depending upon the thickness of the crown wall and the purpose to which the furnace is designed to be used.

With a furnace made in accordance with 75 my invention, the crown wall or arch being made in transverse sections with intermediate ribs, provides a very strong and durable arch, and when it is desired to thicken or patch the portions of the wall 80 after it has been partially burned out and becomes too thin for safety, new bricks may be inserted between the ribs 8, and in this way the thin portions of the arch may be quickly repaired, and this is deemed an important feature in my construction. 85

Having thus described the invention, what I claim is:

1. A furnace comprising side walls, angle iron braces at the tops of said walls, angle 90 iron buck stays connected by cross rod braces, and an arch comprising transverse sections of bricks, and intermediate arched ribs, said ribs extending beyond the outer face of the bricks. 95

2. An arch construction for furnaces comprising transverse brick sections and intermediate arched ribs formed of blocks of refractory material, the inner surfaces of the rib blocks lying flush with the bricks and the 100 outer surfaces of the rib blocks extending beyond the outer surface of the bricks.

In testimony whereof, I affix my signature in presence of two witnesses.

FRANK ORTH.
